United States Patent Office

Des. 210,261
Patented Feb. 20, 1968

210,261

COSMETIC HOLDER OR SIMILAR ARTICLE

Richard L. Thurman, Beloit, Wis., assignor, by mesne assignments, to The Smylon Co., Hollywood, Calif., a corporation of California

Filed Oct. 28, 1964, Ser. No. 82,355

Term of patent 14 years

(Cl. D86—10)

FIG. 1

FIG. 2

FIG. 5

FIG. 3

FIG. 4

FIGURE 1 is a front elevational view of a cosmetic holder or similar article, showing my new design, the side opposite thereto being similar in appearance;

The broken line showing of a cosmetic stick in FIGS. 1, 2, and 5 is for illustrative purposes only.

I claim:

The ornamental design for a cosmetic holder or similar article, as shown and described.
